US00D851253S

(12) **United States Design Patent** (10) Patent No.: **US D851,253 S**
(45) Date of Patent: **** Jun. 11, 2019**

(54) **MOBILE CARDIAC SENSOR**

- (71) Applicant: **Eko Devices, Inc.**, Berkeley, CA (US)
(72) Inventor: **Philip Goolkasian**, Berkeley, CA (US)
(**) Term: **15 Years**
(21) Appl. No.: **29/633,700**
(22) Filed: **Jan. 15, 2018**

(57) **CLAIM**

The ornamental design for a mobile cardiac sensor, as shown and described.

DESCRIPTION

FIG. 1 is a front perspective view of a mobile cardiac sensor showing the new design; and,

FIG. 2 is a front view thereof.

Portions of the mobile cardiac sensor shown in broken lines form no part of the claimed design.

1 Claim, 2 Drawing Sheets

FIG. 1

FIG. 2
